UNITED STATES PATENT OFFICE.

BERRY A. BAXTER, OF MANSFIELD, OHIO.

MANIFOLDING ACCOUNT-BOOK.

No. 823,756.

Specification of Letters Patent.

Patented June 19, 1906.

Application filed January 26, 1903. Serial No. 140,568.

To all whom it may concern:

Be it known that I, BERRY A. BAXTER, a citizen of the United States, residing at Mansfield, in the county of Richland and State of Ohio, have invented certain new and useful Improvements in Manifolding Account-Books, of which I declare the following to be a full, clear, and exact description.

My invention relates to that class of manifolding account-books in which entries are made upon an original sheet and are transferred to one or more duplicate sheets by means of manifolding paper; and my improvement has more particular application to that style of manifolding book in which one leaf section or pad is attached at one end of the book and the other leaf section or pad is attached to the other end of the book or at the side of the book in such manner that the leaves of these independent leaf-sections are adapted to interlap.

It is the object and purpose of my present invention to provide means whereby the upper one of these two independent leaf-sections may be so attached to the book as always to assume a perfectly flat position over the entire length of the lower leaf-section regardless of how many leaves have been detached from the book in the course of its use.

In the accompanying drawings, Figure 1 represents a perspective view of the entire book. Fig. 2 represents a perspective view of the detachable back. Fig. 3 represents a detailed perspective view of the clip used to attach the leaf-section to the back.

Referring to Figs. 1 and 2, A represents the back of the book, which consists of a single piece of sheet metal bent into such shape as to serve as a holder for the two independent leaf-sections. One end of this metal back A is bent upward and then backward upon itself in such manner as to form a pocket 1, the shape of which is better shown in Fig. 2, and the purpose of this pocket is to have inserted into it the binding end of the lower leaf section or pad C, which is composed of a number of separate leaves bound together at one end and upon which leaves the original entries are to be made. The pocket 1 is to be so constructed as to hold the leaf-section C firmly in place when the bound end thereof is in-

serted into it, but at the same time to permit the said leaf-section to be withdrawn and a new one inserted in its place. Various devices for accomplishing this are well known in the art, and as one means therefor I have shown the upper flange 2 of the pocket 1 bent slightly downward in such manner as to make the pocket into the shape of a beveled slot just wide enough to allow the bound end of the leaf-section C to be slid into position from the side, where it remains firmly held in position by the pressure of the flange 2 upon it, but may be withdrawn by hand, or, as another means of attaching said leaf-section C firmly to the pocket 1, the leaves may be first bound firmly together by a clip 11 (shown in Fig. 3) and attached to said pocket by means of the tongues 12, as hereinafter described. Bound together with the leaf-section C, but attached thereto by a flexible hinge a, is a suitable cover B, adapted to fold over the entire book.

The leaf-section C extends almost to the outer end of the metal back A. At this outer end the back A is bent vertically upward at 3 and then bent horizontally backward upon itself to form another pocket 4. It will be observed that this pocket 4 is of greater height than the pocket 1, the purpose of which is that it may have inserted into it a second leaf-section or pad D, composed of a number of separate leaves upon which the original memoranda may be duplicated, and this leaf-section D is so attached to the pocket 4 as to permit a vertical movement of the bound end of the leaf-section D for the purpose hereinafter to be described. The separate leaves of the leaf-section D are bound together at their outer ends by a clip 11. (Shown in detail in Fig. 3.) This clip has projecting from each end a tongue 12, and when the leaf section D is inserted within the pocket 4 the tongues 12 are bent inwardly to clasp loosely the vertical part 3 of the pocket 4. It is thus evident that the leaf-section D is practically prevented from having any lateral movement; but it may have a vertical movement at its outer end, being limited in its downward movement by the base of the pocket 4 and in its upward movement by the flange 5 of said pocket. Attached to the up-

per side of the leaf-section D is a manifolding-sheet G.

In the use of this book one of the sheets of the lower leaf-section C is withdrawn from beneath the upper leaf-section D, is folded over upon the manifolding-sheet G, then the entries are made upon this original sheet, and, by means of the manifolding-sheet G, these entries are duplicated upon one of the sheets of the leaf-section D. This duplicate sheet is then detached from the book and is delivered to the customer. It is thus obvious that as the various leaves of the leaf-section C are withdrawn from beneath the upper leaf-section D and the leaf-section C thereby diminished in thickness it becomes desirable to have the leaf-section D so attached at the outer end of the book that it will be vertically adjustable and will slide downward as fast as the leaves of the section C are used up and in such manner that it will always assume a level position for its entire length over the surface of the lower leaf-section C. The advantages of such a construction are obvious in that no matter how many sheets have been extracted in the course of the use of the book, as hereinbefore described, there is always presented a perfectly flat writing-surface, and the original and the duplicate sheets always maintain comparatively the same relative positions in such manner that the entries upon the original sheet will always be transferred to the proper line upon the duplicate sheet, and while I have shown and described herein the preferred form of embodiment of my invention it is to be understood that other specific forms may be used without in any way departing from the spirit of my invention.

In order that the inner end of the original sheet of the leaf-section C may be more nearly on a level with the upper surface of the leaf-section D when said original sheet is in the position above described ready for use, the inner end of the metal back A is bent slightly upward at 6, and the binding portion of the leaf-section C is thereby raised until it is more nearly on a level with the upper leaf-section D.

It is to be observed also that by releasing the tongues 12 of the clip 11 and by withdrawing the leaf-section C from within the pocket 1, as hereinbefore described, the remnants of both leaf-sections may be detached from their respective pockets when the various leaves have been used up, and new leaf-sections may be inserted into the same metal back.

Having thus described my invention, what I claim as new is as follows:

6. 1. In a manifolding account-book the combination with a metal back, of an under leaf-pad detachably secured at one end of said back, an upper leaf-pad, and means for detachably securing the same to said back with

provisions permitting adjustment thereof to 65 and from the under leaf-pad.

2. A manifolding account-book consisting of a metal back having at one end a pocket adapted to hold a detachable leaf-pad and having at the other end an enlarged pocket 70 adapted to hold a detachable leaf-pad, two independent leaf-pads for said pockets, and means for attaching one of said leaf-pads within said enlarged pocket with provisions permitting the adjustment of said leaf-pad 75 to and from the other leaf-pad.

3. A manifolding account-book consisting of a metal back having at one end a pocket adapted to hold a detachable leaf-pad and having at the other end an enlarged pocket 80 adapted to hold a detachable leaf-pad, two independent leaf-pads for said pockets, means for attaching one of said leaf-pads within said enlarged pocket with provisions permitting the adjustment of said leaf-pad to 85 and from the other leaf-pad, and a carbon sheet adapted to be interposed between a sheet of the upper leaf-pad and a sheet of the under leaf-pad.

4. In a manifolding account-book the combination with two independent leaf-pads superposed one over the other, of a single-piece metal back adapted to hold said leaf-pads, and bent slightly at one end to raise the level of the binding end of the under leaf-pad, 95 and means for attaching the upper leaf-pad to the other end of said back, with provisions permitting adjustment thereof to and from the other leaf-pad.

5. As an article of manufacture, a back for 100 manifolding account-books, consisting of a single piece of metal having a body part, and bent at one end into the shape of a pocket to receive a single leaf-pad, and at the other end into an enlarged pocket having a straight 105 end wall and of depth substantially double that of the thickness of one such pad, said body part being slightly bent upward near the end which has the pocket for the single leaf-pad.

6. In a manifolding account-book, the combination with two independent leaf-pads superposed one over the other, of a suitable back, and means for attaching the upper leaf-pad to said back including provisions for permitting the adjustment of said leaf-pad to 115 and from the lower leaf-pad but preventing displacement in any other direction.

7. In a manifolding account-book, the combination with two independent leaf-pads 120 superposed one over the other, of a suitable back, and means attached to one of said leaf-pads and adjustably engaged with said back to permit adjustment of said leaf-pad to and from said back but preventing displacement 125 in any other direction.

8. In a manifolding account-book, the combination with two independent leaf-pads

superposed one over the other, of a suitable back, and a binding-clip fastened to one of said leaf-pads and formed with provisions for adjustably engaging said leaf-pad with 5 said back to permit adjustment of said leaf-pad to and from said back but preventing displacement in any other direction.

In testimony whereof I affix my signature in the presence of two witnesses.

BERRY A. BAXTER.
